UNITED STATES PATENT OFFICE.

JOHN BEST, OF PATERSON, NEW JERSEY.

DESIGN FOR A BOOK-MARK.

SPECIFICATION forming part of Design No. 22,775, dated September 12, 1893.

Application filed May 13, 1893. Serial No. 474,148. Term of patent 3½ years.

To all whom it may concern:

Be it known that I, JOHN BEST, a citizen of the United States, residing at Paterson, in the county of Passaic and State of New Jersey, 5 have invented and produced a new and original Design for Book-Marks; and I do declare the following to be a full, clear, and exact description of the same, reference being had to the accompanying drawings, forming a part 10 thereof.

The object of my design is to produce an ornamental book-mark having thereon features illustrative of the poem "Home Sweet Home" woven therein or otherwise placed 15 thereon.

The leading or characteristic features which constitute my design, are a country landscape, consisting of a cottage, woods in the back ground, garden in front of the cottage 20 with shrubbery and bee-hives in the fore-

ground, and a path leading to the door of the cottage at which stands the figure of a woman looking anxiously and expectantly toward the gate. Lower down on the left hand side of the book-mark is the representation 25 of a weary traveler, a man, sitting by the wayside under the shade of a spreading tree. At the bottom of the book-mark is the ornamentation of a combined scroll and leaf like character and at the top is a fanciful border. 30

I claim—

The design for book-mark substantially as herein shown and described.

In testimony whereof I affix my signature in presence of two witnesses.

JOHN BEST.
